DESIGN FOR A CARD TABLE COVER

Theodore S. Cart, Princeton, N. J., assignor to Atlantic Products Corporation, Trenton, N. J., a corporation of New Jersey

Application May 5, 1938, Serial No. 77,008

Term of patent 14 years

To all whom it may concern:

Be it known that I, Theodore S. Cart, a citizen of the United States, residing at Princeton, in the county of Mercer and State of New Jersey, have invented a new, original, and ornamental Design for a Card Table Cover, of which the following is a specification, reference being had to the accompanying drawing, forming part thereof.

The figure is a plan view of a card table cover showing my new design.

The circular areas 1, shown in the drawing, comprise tufted fibrous material, of a color contrasting with the color of the body portion of the card table cover.

I claim:

The ornamental design for a card table cover, as shown and described.

THEODORE S. CART.
